UNITED STATES PATENT OFFICE

153,303

DESIGN FOR A MANHOLE COVER

Harry G. Miller, Sr., Kansas City, Kans.

Application August 16, 1948, Serial No. 148,129

Term of patent 7 years

(Cl. D60—2)

To all whom it may concern:

Be it known that I, Harry G. Miller, Sr., a citizen of the United States, residing at Kansas City, in the county of Wyandotte and State of Kansas, have invented a new, original, and ornamental Design for a Manhole Cover, of which the following is a specification, reference being had to the accompanying drawing, forming a part thereof.

Figure 1 is a plan view of a manhole cover, showing my new design.

Fig. 2 is an edge view of the manhole cover.

I claim:

The ornamental design for a manhole cover, as shown.

HARRY G. MILLER, SR.
